JUG

Walter P. Conway, New York, N.Y., assignor to Bemis
Bro. Bag Company, Minneapolis, Minn., a corporation of Missouri

Filed Oct. 23, 1963, Ser. No. 77,113

Term of patent 14 years

(Cl. D58—5)

FIG. 1 is a top plan view of a jug showing my new design;

FIG. 2 is an elevation of one face of the jug;

FIG. 3 is an elevation of the other face of the jug;

FIG. 4 is a bottom plan view of FIG. 3;

FIG. 5 is a left side elevation of FIG. 2; and

FIG. 6 is a right side elevation of FIG. 2.

I claim:

The ornamental design for a jug, substantially as shown.
